Application August 24, 1943, Serial No. 499,762

3 Claims. (Cl. 23—14.5)

The invention relates to the separation of substances from each other and more particularly relates to the separation of element 94 and uranium from each other and from other substances.

It is an object of the invention to provide a convenient and inexpensive process for separating various substances of the kind that are usually present in neutron irradiated uranium, such as element 94, uranium, fission products, and the like. It is a more specific object to remove substantially all of the uranium from element 94 and other substances resulting from the neutron bombardment of the uranium. Further objects and advantages will be apparent from the following description and drawing.

In the drawing, the figure is a diagrammatic view in section of an apparatus for carrying out one process embodying the invention.

In the following description, the isotope of element 93 having a mass of 239 is referred to as 93^{239} and the isotope of element 94 having a mass of 239 is referred to as 94^{239} . Element 94 may also be spoken of as plutonium, symbol Pu. References to any of the elements will include the element either in its free state or as a compound. Neutron irradiated uranium may be prepared by reacting uranium with neutrons from any conventional neutron source, but preferably the neutrons used are obtained from a chain reaction of neutrons with uranium.

Neutron irradiated uranium contains 93^{239} produced through beta decay as a result of the reaction of neutrons with U^{238} , 94^{239} formed from the beta decay of 93^{239} , and also a large number of radioactive fission products resulting from the neutron bombardment of uranium. It also contains minor amounts of the natural radioactive decay products such as UX_1 and UX_2 . The 93^{239} plus 94^{239} is generally present in very small amounts and, since the 93^{239} has a half life of only 2.3 days and decays to 94^{239} , the 94^{239} generally will be present in larger proportion than the 93^{239} . By storing the neutron irradiated uranium for several days, the 93^{239} may be converted almost entirely to 94^{239} . The fission products are present in very small amounts, but, because of their high radioactivity, it is highly desirable that these products be removed.

The fission products consist of a large number of elements which may be classified into two groups; a light group with atomic numbers from 35-44; and a heavy group with atomic numbers from 51-58. The fission products with which we are particularly concerned are those having a half life of more than three days since they remain in the reaction mass in substantial quantities at least one month after reaction. These products are chiefly Sr^{89} , Y (57 day half life), Zr , Cb , and Ru of the group of atomic numbers from 35-44; and Tc^{127} , Tc^{129} , I^{131} , Xe^{133} , Cs (many years half life), Ba (12 days half life), La^{140} , and Ce of 20-day and 200-day half lives from the group of atomic numbers from 51-58 inclusive.

2

Briefly, the invention comprises chlorinating uranium which contains plutonium, fission products or other substances, to form uranium pentachloride or higher uranium chlorides. The latter product is volatilized at controlled temperatures and removed from plutonium and other substances in vapor form as a separate fraction. Plutonium is separated from the remaining substances by being volatilized as a reaction product at higher temperatures and removed in vapor form as a second separate fraction.

The separation of the uranium from plutonium probably results either from the fact that the temperature of formation of uranium pentachloride or higher uranium chloride is lower than the temperature of reaction of plutonium with the chlorine or from the fact that the temperature of volatilization of the reacted uranium is lower than that of the reacted plutonium. Irrespective of the explanation, it has been found that uranium and plutonium will be volatilized and separated from each other and from other substances present when treated in accordance with the invention.

While the uranium to be treated is preferably neutron irradiated uranium, it is contemplated that any uranium containing plutonium with or without other substances present may be separated from such plutonium when treated as described herein.

As only relatively small amounts of plutonium, fission products, and other substances are contained in the uranium, it is desirable to have the uranium in a form which is most easily treated. The uranium may be treated most satisfactorily when in the form of the metal or, preferably, as one of the uranium oxides. If the uranium is originally in the form of a compound other than an oxide, it is desirable to convert such compound to the oxide before separating the substances present. Where the uranium is in the form of a metal, it may be advantageous to convert such metal to uranium oxide although the metal may be treated directly. Of the several uranium oxides, uranium tritaoctoxide, U_3O_8 , is most conveniently used.

In using uranium oxide, it is desirable to have present a substance which will unite with the oxygen so that the latter will be removed from the uranium, as where carbon is supplied to remove the oxygen in the form of carbon dioxide or carbon monoxide or both. Various oxygen-removing substances may be used either in liquid form, such as carbon tetrachloride, chloroform, antimony chloride, and the like, or in solid form, such as charcoal or graphite. It is contemplated that an oxygen-removing substance may be used in gaseous form.

Where uranium metal is treated, the uranium unites directly with the gaseous chlorine to form uranium pentachloride or higher uranium chloride. In this reaction, the use of an oxygen-removing substance may be omitted.

In carrying out the process with uranium oxide, containing plutonium, fission products, and the like, and using carbon tetrachloride as the oxygen-removing substance, the uranium oxide 1 is contained in a receptacle 2 which will expose a large amount of surface of the uranium oxide. The receptacle is placed in a reaction chamber 3, which like all other parts of the apparatus is formed of material, such as glass or the like, which will not be seriously corroded or otherwise deteriorated by the action of chlorine or other substances present. If desired, the uranium oxide may be placed directly in the reaction chamber without being contained in receptacle 1. The reaction chamber 3 has an aperture 4 so positioned that gases entering the chamber through such aperture will come into intimate contact with the uranium oxide.

Where carbon tetrachloride or other oxygen-removing substance in liquid form is used, aperture 4 is connected

to a closed receptacle 5 containing a suitable amount of carbon tetrachloride 6. Gaseous chlorine is introduced into receptacle 5 from chlorine tank 7 by means of pipe 8 which extends almost to the bottom of receptacle 5 thereby causing the chlorine to pass up through the carbon tetrachloride and through aperture 4. The carbon tetrachloride is kept warm by suitable heating means (not shown) so that it will vaporize more easily and be carried with the chlorine into the reaction chamber 3 and into intimate contact with the uranium oxide.

Where the oxygen-removing substance is in solid form, such as charcoal or graphite, the substance is intimately mixed with the uranium oxide in one to twice the theoretical proportions necessary for the carbon to unite with the oxygen of the oxide to form carbon dioxide. Thus, from 48 to 96 grams of carbon may be used for every 842 grams of uranium triaotctoxide, U_3O_8 . The chlorine is passed directly from tank 7 through aperture 4 into the reaction chamber 3.

In using the uranium metal without an oxygen-removing substance, the uranium is placed in reaction chamber 3 and the chlorine supplied directly from tank 7.

An excess of chlorine over that necessary to completely react with the uranium and the substances contained therein is passed into reaction chamber 3. The pressure under which the chlorine is present in the reaction chamber influences the reaction. If greater pressure is used, the reaction proceeds faster and heat is evolved more rapidly. As the temperature of the uranium oxide during the reaction must be controlled, it is desirable that the chlorine pressure be adjusted to the temperature of the uranium oxide during the reaction. Satisfactory results are obtained by using one atmosphere pressure of the chlorine in the reaction chamber and controlling the temperature of the uranium oxide during the reaction by heating means.

During the reaction of the uranium oxide with the chlorine and the oxygen-removing substance, reaction chamber 3 is maintained at a sufficiently high temperature by a suitable heating device, such as heating coil 9, to cause the reacted uranium to be volatilized, such temperature being sufficiently low to prevent any substantial volatilization of the plutonium and other substances present. It has been found that the uranium will be volatilized where the temperature is below 500° C. while the plutonium remains in a substantially non-volatile state. Preferably, the temperature of the uranium oxide during the reaction is approximately 450° C. where the chlorine is under a pressure of one atmosphere in the reaction chamber.

As chlorine is passed over the uranium, the latter reacts with the chlorine to form one or more uranium chlorides higher than uranium tetrachloride, such as uranium pentachloride and possibly small amounts of uranium hexachloride. Either of these chlorides are suitable as their volatility is sufficiently greater than that of plutonium or its reaction product to permit the uranium to be volatilized and removed while the plutonium is non-volatile. If desired, the details of the process may be varied to cause formation of a preponderance of a volatile uranium chloride, such as uranium hexachloride, other than uranium pentachloride. In its broadest aspect, the invention includes reacting uranium and chlorine to form a uranium reaction product which will be sufficiently more volatile than plutonium or its chlorine reaction product or products to permit the uranium to be volatilized and removed while the plutonium is in a substantially non-volatile state. Where higher uranium chloride is mentioned in the following, it is to include uranium chlorides higher than uranium tetrachloride, such as uranium pentachloride or uranium hexachloride or mixtures of such chlorides.

Where uranium is in the form of an oxide and an oxygen-removing substance is present, additional reaction products are formed such as carbon dioxide, carbon

monoxide, and other more complex compounds. Where uranium metal is treated, only the higher uranium chlorides are formed.

The gaseous uranium chloride, carbon dioxide, excess chlorine, and other volatile substances pass out of the reaction chamber through aperture 10 and into trap chamber 11, which contains rock wool or other inert material having a large surface area. As the higher uranium chloride passes out of the reaction chamber 3, it carries with it substances which are desired to be separated from the uranium, such as plutonium, fission products, or other substances originally present in the uranium oxide. While many of such substances may not be considered volatile at the temperature of the reaction chamber, they, nevertheless, pass out of the chamber with the higher uranium chloride. In passing through trap chamber 11, at least some of the carried substances are deposited upon the glass wool while the higher uranium chloride, excess chlorine, carbon dioxide, the relatively more volatile fission products, and the like, pass on through. The trap chamber is preferably maintained at a temperature of approximately 200° C. by suitable heating means, such as a heating coil 12.

After passing out of the trap chamber through aperture 13, the higher uranium chloride is forced by valve 14 to pass through pipe 15 into condensing chamber 16 which is preferably maintained at room temperature. The higher uranium chloride together with any of the more volatile fission products is deposited upon the interior surfaces of condensing chamber 16 while the carbon dioxide, excess chlorine, and other waste gases pass out of the condensing chamber through aperture 17 and are disposed of. The higher uranium chloride and any fission products may be removed from the interior surfaces of condensing chamber 16 by washing with water, scraping, volatilizing, or the like.

The substances remaining in reaction chamber 3 include plutonium which is separated from the other substances present by being volatilized at a higher temperature. The flow of chlorine is maintained through the reaction chamber but the temperature of the substances present is raised to 700° C.-800° C. by heating coil 9. Plutonium is volatilized at this temperature in the presence of chlorine and passes out of the reaction chamber through aperture 10. The volatilized plutonium passes through trap chamber 11 and into aperture 13 where it is forced by valve 14 through pipe 18 into condensing chamber 19 which is maintained at room temperature. The volatilized plutonium is deposited upon the interior surfaces of condensing chamber 19, while the excess chlorine and other waste gases pass out through aperture 20 and are disposed of. The deposited plutonium may be removed from condensing chamber 19 by washing with water, scraping, volatilizing, or the like.

The higher uranium chloride which has been collected as a separate fraction in condensing chamber 16 contains negligible amounts of plutonium and moderate amounts of radioactive fission products. If desired, the uranium may be further purified.

Plutonium, which has been collected as a substantially separate fraction in condensing chamber 19, contains small amounts of fission products and substantially no uranium.

The substances remaining in reaction chamber 3 comprise substantial amounts of the radioactive fission products originally present in the uranium oxide. These may be removed from the reaction chamber and considered as a substantially separate fraction. Minor amounts of other substances may also be present in the residue.

It is contemplated that the first step of the process, that is, volatilizing and removing the uranium from the residue containing plutonium and other substances, may be used as a complete process for purifying plutonium and the other substances to the extent of removing substantially all of the uranium or of obtaining substan-

tially all of the uranium as a separate fraction. It is also contemplated that this step may be used in conjunction with other methods of separating plutonium from the fission products or other substances in the residue to obtain the plutonium and such other substances as substantially separate fractions.

In one embodiment of the invention, one gram of U_3O_6 containing minute amounts of plutonium and fission products is treated with gaseous chlorine under one atmosphere pressure, the chlorine having passed through approximately 5 cc. of carbon tetrachloride 6. The uranium oxide 1 is treated with chlorine and carbon tetrachloride for approximately one-half hour during which time the temperature of reaction chamber 3 is maintained at 450° C. Volatile higher uranium chloride is formed which passes through trap chamber 11 and into condensing chamber 16. The condensed higher uranium chloride contains approximately 30 percent of radioactive fission products and approximately 7 percent of plutonium. Substantially all of the uranium is removed from the reaction chamber during the reaction.

After the higher uranium chloride is removed, the temperature of reaction chamber 3 is raised to approximately 700° C. and chlorine is passed over the remaining substances under pressure of one atmosphere for approximately one-half hour. At the end of this time, substantially all of the plutonium is volatilized and has passed out of the reaction chamber through trap chamber 11 and into condensing chamber 19. The condensed plutonium contains approximately 5 percent of radioactive fission products and substantially no uranium.

The residue is removed from reaction chamber 3 and contains a substantial amount of the radioactive fission products together with minute amounts of other substances.

The substances, such as plutonium, UX_1 , and the like, which are carried from reaction chamber 3 by the volatilized uranium reaction product may usually be considered as non-volatile. While the reason for such behavior is not definitely known, such "carrying" may result from the fact that where extremely minute amounts of substances are treated the volatilization behavior, especially when considered with respect to the forces of attraction between the surfaces of the apparatus and the substances, is not the same as where larger amounts of the substances are treated. Consequently, in a relatively large scale process, it is possible that the problem of preventing substances from being carried out of the reaction chamber by the volatilized uranium product may not be present. In such a case, the trap chamber 11 may be dispensed with and the volatilized reaction product carried directly to condensing chambers 16 and 19.

The "carrying" phenomenon may be prevented or reduced by means other than the use of glass wool or other inert material having a large surface area. Various holdback materials may be incorporated with the uranium oxide 1 or the uranium metal in reaction chamber 3. As used in the specification and claims, the term "holdback material" refers to materials that are incorporated with the uranium compound prior to volatilization of the uranium chloride and that do not interfere with the volatilization and removal of the uranium, but do prevent or reduce the carrying over or removal of other substances present.

Holdback materials which have been used satisfactorily are lanthanum oxide, La_2O_3 , and thorium oxide, ThO_2 . In one case, 1.4 mg. of lanthanum oxide were mixed with 30 mg. of uranium tritaectoxide and treated with chlorine and carbon tetrachloride. The loss of UX_1 , one of the substances carried by the volatilized uranium, was one percent as compared with a 50 percent loss where the

holdback material was not used. In another case, 2.2 mg. of thorium oxide were mixed with 30 mg. of uranium tritaectoxide and the mixture treated as before. The loss of UX_1 was 0.5 percent as compared again to the 50 percent loss where no holdback material was used. The volatilization or removal of substances from the reaction chamber other than UX_1 is likewise prevented or reduced by such holdback materials.

Where the uranium treated is neutron irradiated uranium, the particular amounts of fission products and plutonium which are present in the uranium will depend somewhat upon the amount of time which is allowed to lapse between the neutron bombardment of the uranium and the process of separation.

The above detailed description is given for purposes of illustration and the invention is to be limited only by the scope of the appended claims.

What is claimed is:

1. A method of separating uranium values from plutonium values comprising contacting said uranium with chlorine in the presence of a holdback material selected from the group consisting of lanthanum oxide and thorium oxide to form a uranium chloride higher than uranium tetrachloride, and thereafter heating the uranium chloride thus formed to a temperature at which said uranium chloride is volatilized off but below the volatilization temperature of plutonium chloride.

2. A method of separating uranium values, plutonium values, and fission products comprising contacting a uranium oxide containing plutonium and fission products with chlorine in the presence of a holdback material selected from the group consisting of lanthanum oxide and thorium oxide to form a uranium chloride higher than uranium tetrachloride, thereafter heating the uranium chloride thus formed to a temperature below 500° C. but sufficiently high to volatilize off said uranium chloride from said plutonium values and at least a part of said fission products, contacting said plutonium with chlorine to form a plutonium chloride, and thereafter heating the plutonium chloride thus formed to a temperature of about 700° C. to volatilize off said plutonium chloride from at least a part of said fission products.

3. A method of separating uranium values, plutonium values, and fission products comprising contacting said uranium with chlorine in the presence of a holdback material selected from the group consisting of lanthanum oxide and thorium oxide to form a uranium chloride higher than uranium tetrachloride, thereafter heating the uranium chloride thus formed to a temperature below 500° C. but sufficiently high to volatilize off said uranium chloride from said plutonium values and at least a part of said fission products, contacting said plutonium with chlorine to form a plutonium chloride, and thereafter heating the plutonium chloride thus formed to a temperature of about 700° C. to volatilize off said plutonium chloride from at least a part of said fission products.
